UNITED STATES PATENT OFFICE.

WILLIAM F. SMITH, OF SALEM, NEW HAMPSHIRE, ASSIGNOR TO IRVING L. KEITH, OF HAVERHILL, MASSACHUSETTS.

CEMENTING-MACHINE.

1,288,247.

Specification of Letters Patent. Patented Dec. 17, 1918.

Application filed February 2, 1917. Serial No. 146,270.

To all whom it may concern:

Be it known that I, WILLIAM F. SMITH, a citizen of the United States, and a resident of Salem, county of Rockingham, and State of New Hampshire, have invented an Improvement in Cementing-Machines, of which the following is a specification.

This invention relates to that class of cementing machines in which an apertured 10 plate or grid, having horizontal cement carrying faces, is arranged to be raised and lowered in a receptacle containing liquid cement, the material to be cemented being laid on said face while the latter is held above 15 the level of the cement.

In cementing textile fabric to the inner side of light weight upper leather, if the entire surface is coated with cement by a brush, the fabric is liable to cockle when it 20 dries; on account of shrinkage of threads. To avoid this difficulty, devices of the character above referred to have been produced, which are designed to apply the cement over a portion only of the surface to which the 25 cement is applied. Some of these prior devices comprise straight bars, on which upright cement applying fingers are formed and others which comprise straight, or gradually curved bars, having continuous cement 30 applying upper edges. In cementing long narrow pieces of textile material, such as textile eyelet stays, to the inner sides of shoe uppers, with devices of this character, unsatisfactory results have previously been 35 secured for, when employed for this particular purpose, the stays were not attached with sufficient security and, on account of the fact that these stays are curved, when continuous, approximately straight strips of cement 40 were applied thereto, some of these strips are likely to extend nearly longitudinally of one set of threads, particularly if special care is not exercised by the operator, thereby causing a portion of these threads to shrink, 45 so that the stay will not lie flat on the surface to which it is cemented.

It is customary, in connection with cementing machines of this character, to employ a cement which is in the form of a 50 heavy, slow flowing liquid, so that special provision must be made to permit the rapid escape of the cement from the cement applying surfaces, when the grid is raised, and so that no cement will be held between said 55 surfaces in a position to touch the surface

to be cemented and free up and down movement of the grid will be permitted.

The object of my invention is to provide a form of cementing machine, of the general character above referred to, which is adapted to apply cement to narrow, curved pieces of textile material in such a manner and in a sufficient quantity to cause the same to adhere firmly in position and without causing them to wrinkle, so that they will lie flat 60 on the surfaces to which they are cemented. A further object is to provide a machine of this character which will provide a maximum area for the escape of cement and, at the same time, will provide a very substantial 65 increase in the area of the cement-apply- 70 ing surface.

I accomplish these objects by the means shown in the accompanying drawings, in which—

Figure 1 is a plan view, partly broken away, of an embodiment of my invention.

Fig. 2 is a cross-sectional view on line 2—2 of Fig. 1.

Fig. 3 is a detail side view of one of the 80 bars.

Fig. 4 is a view illustrating the manner in which the cement is applied.

As shown in the drawing, a suitable 85 bench, or table *a* is provided, on which shallow oblong receptacle *b* is supported, said receptacle being adapted to contain liquid cement to a suitable depth. A bar carrying frame is provided, which is composed of a pair of parallel side rods *c*, and a pair of 90 cross bars *d*, in which the ends of said side rods are held; said cross bars having arms *d'* extending upwardly therefrom and over the ends of the receptacle and being connected to the arms of a yoke *e*, which extend 95 through the table and are adapted to be raised and lowered by a suitable treadle mechanism, not shown, in a well known manner. The frame is thus supported in a horizontal position and is arranged to be raised 100 and lowered by the treadle mechanism while held in this position.

Mounted edgewise on the rods *c*, in parallel relation to the cross bars *d*, are a series of flat, sheet-metal bars *f*, said rods being 105 passed through the end portions of said bars and the latter being spaced apart by interposed rings or washers *g*, the width of the spaces between said bars, in proportion to the thickness of the bars themselves, being, 110

in practice, about three to one. The upper edges of said bars are continuous and disposed in the same horizontal plane.

The intermediate portions of said bars *f* are bent in zig-zag form, or are bent to form a regular series of sharp angles or V shaped portions therein, said angles pointing in opposite directions, alternately. The cement applying portion of each bar is thus composed of a series of straight sections disposed in alternate positions of obliquity to the general direction, or ultimate line in which the bar extends. As all the bars are of identical construction, the angles formed therein are correspondingly disposed in rows, so that the vertices of the angles in each row lie in a straight line, which is parallel to the rods *c*. As the zig-zag formation of all the bars is identical, the space between each pair of bars, at all points, is uniform and the width of this space is such, as compared with the distance the bars are extended laterally from a straight line between the ends thereof, that the vertex of each angle extends slightly within the sides of the corresponding angle of the next adjacent bar, or, in other words, said bars are so arranged that the vertices of all the angles not only lie approximately in straight lines, which extend transversely of the bars, but also in straight lines which extend longitudinally thereof, or at right angles to the transverse lines.

The bars are made as narrow as practicable throughout their zig-zag portions and are increased in width at their ends from the level of their upper edges, downwardly to an extent sufficient to receive the side rods *c*, as shown in Fig. 3. The upper edges of said bars, which constitute the cement carrying surfaces must be freed from surplus cement as rapidly as possible when raised, and by reducing the width of said bars or distance between their upper and lower edges, as the thick, slow flowing cement, which is employed, may flow away from said upper edges much more rapidly than it would if the vertical width of the bars were as great in the middle portion as at the ends.

In use, the bars *f* are entirely submerged in the liquid cement, in the receptacle, and, when the bars are raised above the surface thereof, the material to be cemented is laid thereon, as indicated in Fig. 1, so that the cement will be applied thereto.

The particular advantages of the above described construction may be described as follows:—As already indicated, puckering and wrinkling of textile material is usually due to unequal shrinkage of the threads. If the liquid cement were applied thereto in long straight lines, or even in gradually curved lines, it would be applied to many of the threads throughout a considerable portion of the length thereof, depending some-

what on the particular position in which the material happened to be placed thereon, so that substantial shrinkage of the threads would be caused when they dried. With the above described zig-zag construction, however, cement will be continuously applied only to short portions of individual threads, whatever the position in which the material is placed thereon, as indicated in Fig. 4, for each strip of cement extends in one direction for only a short distance. It will be also apparent that, with the above described zig-zag construction, the total area of the cement applying faces is much greater, for the same area of the grid, than if the bars were straight or somewhat curved, while, at the same time, the space provided at each side of each bar for the escape of cement therebetween, as the grid is lifted, is not, in any substantial degree reduced.

As already stated, however, this particular construction is especially designed for use in cementing textile eyelet stay pieces, and the like, a form of which is indicated in Figs. 1 and 4. It will be observed that, when such a piece is applied to the cement-applying faces, formed by the upper edges of the bars *f*, narrow strips of cement will be applied thereto, which generally extend obliquely to the edges of the piece, whatever the position in which it may be applied thereto, and, at no point, do the strips of cement coincide with the threads of the piece, for more than short distances. As each strip of cement extends, either partly or wholly, in directions oblique to the side edges of the piece of material, the latter will be much more securely cemented in position than if the strips of cement extended either nearly directly crosswise or lengthwise thereof and if the piece of material were curved as much as such pieces frequently are, and if cement were applied thereto with straight or nearly straight parallel bars, the probability that the cement would be applied in one or the other of these directions would be great. Obviously the conditions will be somewhat varied according to the position in which the piece is applied to the bars, but in performing work like this, which must be performed very rapidly, it cannot be expected that an operator will exercise much care as to the position in which the piece to be cemented, will be placed, and with straight, or nearly straight cementing bars, the chances that it may be placed very disadvantageously are great, while with the zig-zag form of bars above described, the cement will be advantageously applied under all conditions, or wherever the piece is placed thereon.

In some instances it is desired to apply a coating of the cement which is much thinner than can be applied with a brush, to practically the entire surface of the stay piece, and this may be easily accomplished with the

above described device by applying the piece to the bars in any position and then drawing or sliding it longitudinally over the bars for a short distance. It will be observed that 5 with this construction, whatever the position in which the piece is laid on the bars or whatever the direction in which it is slid or pulled longitudinally, a movement thereon for a distance no more than the width of the 10 spaces between the bars will cause the edges of the bars to come into contact with the entire surface of the piece, and this will occur if the piece is curved and moved in a correspondingly curved direction, while if the 15 bars were straight, the piece would have to be moved in a direction approximately perpendicular thereto, to accomplish the same result.

While some variation in the form of the 20 cement applying bars from that shown, may be made without departing from the spirit of my invention, the particular form shown is preferable.

I claim.

1. In a cementing machine, a receptacle 25 for containing liquid cement and a vertically movable cementing grid therein, comprising a series of bars of flat material arranged edgewise and spaced apart, to provide free passages for the cement at each side thereof, each of said bars having the cementing portions thereof disposed in alternating positions of obliquity with relation to the direction in which the bar extends, 30 and having the upper edges of said portions 35 in the same horizontal plane.

2. In a cementing machine, a receptacle 40 for containing liquid cement, and a vertically movable, horizontally disposed cementing grid therein, comprising a series of bars arranged side by side in approximate parallelism and spaced apart to provide free 45 passages for the cement therebetween and separate cement-applying faces at their upper portions disposed at the same level, the portions of said bars bearing said faces being composed of a series of obliquely extending sections arranged alternately at opposite inclinations.

3. In a cementing machine, a receptacle 50 for containing liquid cement and a vertically movable, horizontally disposed cementing grid therein, comprising a series of elongated bars arranged side by side in approximate parallelism and spaced apart to 55 provide free passages for the cement therebetween and separate cement applying faces at their upper sides disposed at the same level, the portions of said bars bearing said faces being constructed to provide a series 60 of transversely disposed angular portions with their vertices at opposite sides of and at equal distances from a straight line.

4. In a cementing machine, a receptacle 65 for containing liquid cement and a verti-

cally movable, horizontally disposed cementing grid therein, comprising a series of elongated bars arranged side by side in approximate parallelism, spaced apart to provide free passages for the cement therebetween and separate cement-applying faces 70 at their upper sides disposed at the same level, the portion of said bars bearing said faces being alternately extended laterally to form transversely disposed angles therein, 75 the vertices of which lie in approximately parallel lines.

5. In a cementing machine, a receptacle 80 for containing liquid cement and a vertically movable, horizontally disposed cementing grid, therein, comprising a series of elongated bars arranged side by side in approximate parallelism and spaced apart to provide free passages for the cement therebetween and separate cement applying faces 85 at their upper sides disposed at the same level, the portion of said bars bearing said faces being extended to form transversely disposed angles therein, relatively so arranged that the vertices thereof lie in two 90 sets of parallel lines which extend perpendicularly to each other.

6. In a cementing machine, a receptacle 95 for containing liquid cement and a vertically movable, horizontally disposed cementing grid therein, comprising a series of elongated bars arranged side by side in approximate parallelism and spaced apart to provide free passages for the cement therebetween and separate cement-applying faces 100 at their upper sides disposed at the same level, the cement applying portions of said bars being constructed to provide transversely and oppositely disposed angles alternately therein, the vertex of each angle of 105 one bar being disposed within and approximately midway between the sides of the corresponding angle of the next adjacent bar.

7. In a cementing machine, a receptacle 110 for containing liquid cement and a vertically movably, horizontally disposed cementing grid therein, comprising a series of elongated bars arranged side by side in approximate parallelism and spaced apart to 115 provide free passages for the cement therebetween and separate cement-applying faces at their upper sides disposed at the same level, the portions of said bars bearing said faces being extended transversely, at correspondingly successive points, to an extent 120 as great as the width of the passages between the bars.

8. In a cementing machine, a receptacle 125 for containing liquid cement, and a vertically movable, horizontally disposed cementing grid therein, comprising a series of elongated bars arranged side by side in parallelism and spaced apart to provide disconnected cementing faces at their upper 130

- sides disposed at the same level, each bar having transversely and oppositely disposed angular portions arranged alternately, said bars being correspondingly formed, so that
5 the vertices of all the corresponding angles are disposed in lines perpendicular to the bars, and being arranged in such proximity that the vertices of the angles of any one bar, which point in one direction, and the vertices
10 of the angles of the next adjacent bar, which point in the opposite direction, all lie approximately in a straight line which is parallel to the directions in which the bars extend.
15 9. In a cementing machine, a receptacle for containing liquid cement and a vertically movable, horizontally disposed grid therein, said grid comprising a frame consisting of transverse end supports and a pair

of parallel connecting rods mounted at their ends in said supports, and a series of fiat bars arranged side by side in parallelism and through the corresponding ends of which said rods pass to support the same, said bars being spaced apart and having their upper edges in the same horizontal plane to provide separate cementing faces and the portions of said bars between the end portions engaged by said rods being of reduced width to provide relatively short passages vertically between the bars, to permit the ready escape of cement from said faces downwardly through said passages.

In testimony whereof I have signed my name to this specification.

WILLIAM F. SMITH.
